UNITED STATES PATENT OFFICE.

CHARLES KAESTNER, OF CHICAGO, ILLINOIS.

ELEVATOR.

SPECIFICATION forming part of Letters Patent No. 247,655, dated September 27, 1881.

Application filed July 21, 1881. (No model.)

To all whom it may concern:

Be it known that I, CHARLES KAESTNER, of Chicago, in the county of Cook and State of Illinois, have invented a certain new and useful Improvement in Elevators, of which the following is a specification.

The nature of my invention relates to that class of elevators in which a series of buckets will alternately pick up or fill on a lower floor 10 with material that is elevated and dumped on a higher floor, and more particularly to elevators of that kind in which the buckets are secured between two parallel endless chains that are stretched oversprocket-wheels rotated 15 by any suitable motor.

The object of my invention is to provide means that will prevent the dumping or scattering of any material thus hoisted before the buckets have reached the position intended for 20 their discharge—that is, the point where the downward motion commences. For such elevators two sprocket-wheels are mounted upon the upper shaft at the proper distance apart. The space between these wheels was, however, 25 heretofore left open. When, particularly with hoisting water or wet material, the buckets commenced to discharge as soon as they had to follow the periphery of the upper sprocket-wheels, certain portions of the water or other 30 material was precipitated in the space between the two chain-lines, which became a great nuisance and caused a waste of power and material. To overcome this difficulty I interpose 35 between the two sprocket-wheels a pulley or drum, the edges of which form close joints with the rims of said sprocket-wheels, and which will prevent any material from falling from the buckets into the space between the chains or pulley; and for hoisting wet material or liquid of any sort I provide the drum 40 on its face with a series of longitudinal radial ribs, that will come to stand behind and under said buckets, and while the wheels are turning these ribs will raise to an incline upon the 45 face of the drum correspondent with the inclination of the bucket, and while thus on the upper periphery they will form receptacles for any material splashed out of the buckets, which material they will deliver at about the same 50 point where the buckets will dump their entire loads.

In the accompanying drawings, forming a part hereof, Figure 1 represents a longitudinal vertical section of an elevator having my improvements; Fig. 2, a transverse section through the center of the sprocket-wheels and the intermediate drum. Fig. 3 is a sectional plan of a bucket as attached to the chain-links, and Fig. 4 a transverse section of the same.

Like letters designate corresponding parts in all the figures.

A denotes the upper shaft, rotated by any suitable motor, and B B' are the two sprocket-wheels rigidly mounted upon said shaft at the requisite distance apart.

C is the intermediate drum, also mounted upon shaft A, and forming at its rim-edges a close joint with the rims of the two sprocket-wheels B B'. This drum C has a series of longitudinal ribs, c, that are radially projecting from the face of the drum, and are equally distributed around the periphery of the said drum.

D D' are two parallel chains, which may be of the Ewart or any other suitable pattern, and between or upon opposite links of the chains 75 are secured the buckets E E.

The elevator may be placed on a more or less incline, when the chains on the side, where they move upward, may be supported and guided upon planks f, secured upon cross-ties 80 g, that are framed between uprights G.

The elevated material, by its gravity and by the centrifugal force, will be dumped from the buckets at an angle that varies with the speed of the sprocket-wheels, and that will 85 dump it into a receptacle placed at a proper position in front of the buckets below the level of the shaft A, and the material splashed or overrunning from the buckets while the same are carried over the wheel, that would be otherwise precipitated in the space between the two chain-lines moving in opposite directions, will be collected and conveyed by the ribs on the drum, and will be dumped in the same manner as by the buckets, and into the same receptacle, thereby insuring a positive and economical operation.

This device is applicable as well for a single-chain elevator carrying buckets, when rim-extensions could be cast to each side of the 100 sprocket-wheel, with radially-projecting ribs upon their faces, that will catch any material

splashing from the buckets, and convey and dump it in the same manner as when applied to a double-chain elevator.

What I claim as my invention is—

1. The combination of the sprocket-wheels B B', endless-chain elevator D D', and buckets E, and the drum or pulley adapted to occupy the entire space between said sprocket-wheels, substantially as and for the purpose set forth.

2. The combination, with the sprocket-wheels, chain-elevator, and buckets, of a drum or pulley, C, having upon its periphery the longitudinal radial ribs e, substantially as and for the purpose set forth.

3. In an elevator, the combination, with the buckets E, secured between endless chains D D', and driven by sprocket-wheels B B', that are mounted upon a shaft, A, of a drum, C, provided upon its periphery with longitudinal radial ribs e, and occupying the space between said sprocket-wheels B B', all substantially as and for the purpose described and shown.

CHARLES KAESTNER.
